UNITED STATES PATENT OFFICE.

ALBERT F. NORRIS AND CLIFTON H. NORRIS, OF STOUGHTON, MASSACHUSETTS.

DESIGN FOR A PIANO-PEDAL.

45,610.

Specification for Design.

Patented Apr. 14, 1914.

Application filed November 25, 1912. Serial No. 733,540. Term of patent 7 years.

To all whom it may concern:

Be it known that we, ALBERT F. NORRIS and CLIFTON H. NORRIS, both citizens of the United States, residing at Stoughton, in the county of Norfolk and State of Massachusetts, have invented and produced a new, original, and ornamental Design for a Piano-Pedal, of which the following is a specification, reference being had to the accompanying drawing, forming a part thereof.

In the drawings: Figures 1, 2 and 3 are respectively a top plan, a side elevation and a perspective view of the improved pedal.

Referring in detail to the accompanying drawings, and more particularly to Fig. 1

thereof, the numeral 10 designates a pedal the outer or toe portion of which is squared in outline, as at 11, including the right angularly disposed sides 12, the shank 13 of the pedal being tapered from the toe portion, and including the side portions 14 which converge toward the rear end of the pedal.

We claim—

The ornamental design for a piano pedal as shown and described.
